MULTI-FACED FOLDING GUIDE

Raymond A. Labombarde, Nashua, N.H.

Application January 12, 1956, Serial No. 558,726

5 Claims. (Cl. 93—49)

This invention relates to an improved folding guide, or inside former, for use in machines for folding paper boxes.

In the paper box folding art, it has long been customary to advance flat box blanks individually and successively along the paper line of a folding machine while various necessary folds are accomplished on the blanks to produce set-up or collapsed boxes. Especially in the collapsed box field, the blanks usually used have been provided with major wall, top or bottom flaps or panels and minor attachment tabs usually articulated thereto on oblique lines of articulation. Usually the obliquely articulated tabs are folded in one direction while the flaps or panels, to which they are hinged, are folded in the opposite direction. The problem is thus presented of successfully maintaining an overfolded tab in overfolded position while the element to which it is hinged is itself being overfolded, and this problem becomes especially acute when the blanks travel at high speed, whether timed or untimed.

For example in U.S. Patent No. 2,112,121 to Sidebotham granted March 22, 1938, a stationary elongated guide, having a helical face is provided on one side of an advancing blank flap to hold down the overfolded tabs thereon while a flexible belt on the other side of the flap overfolds the same. A somewhat similar guide is provided in U.S. Patent No. 2,197,089 to Anderson issued April 16, 1940, wherein a stationary elongated folding guide includes a helical face for holding down already overfolded tabs on a flap being overfolded and also includes a lower edge extending along the line of flap fold to insure accurate folding thereon. In U.S. Patent No. 2,125,147 to Bergstein granted July 26, 1938, a folding guide in the shape of an elongated rod of small diameter is shown for holding down overfolded tabs on a flap being overfolded.

Usually at least one of the tabs to be held down by such folding guides has been coated with adhesive since the purpose of the tab is to collapsibly attach the box together and the adhesive must be applied before final overfolding of the flaps. Among the disadvantages of the flat bar type of folding guide disclosed in the above patents is the fact that the large area of contact thereof either wipes off any applied adhesive or permits adhesive to be applied only in the small areas of the flaps or tabs not contacted by the guide. In addition the milling of a flat bar into the desired helical face is a time consuming and expensive task as is the shaping of a rod such as taught by the above Bergstein patent into the desired helical configuration.

It is the principal object of this invention to provide a multi-faced, multi-purposed, folding guide capable of not only holding down a first overfolded glue tab on the outside of a longitudinally extending fold line while serving as a fold former on the inside of the fold line, but also holding down a second overfolded tab or flap on the inside of the fold line.

Another object of the invention is to provide such a

2

multi-purpose folding guide wherein the helical face holding down the adhesive tab on the outside of the fold line has an unusually narrow tab contacting face to avoid wiping off the adhesive and is yet of sufficient rigidity to avoid vibration or bending.

Still another object of the invention is to provide a thin walled inverted channel shaped folding guide for holding down outside overfolded tabs on a blank and a spring metal, thin, flat guide for holding down inside 10 overfolded tabs on a blank, the flat guide being fixed along one edge of the channel guide to also serve as a fold forming guide.

A still further object of the invention is to provide an elongated folding guide which utilizes at least three different portions for guiding folds of a blank, which is rigid enough to be supported only at one end and yet is of thin material to reduce weight, reduce frictional contact with the blank and reduce interference with adhesive coatings on the blank.

Other objects and advantages of the invention will be apparent from the claims, the description of the drawings and from the drawings in which—

Fig. 1 is a fragmentary perspective view of that portion of a typical box folding machine in which an outer flap is folded inwardly on a longitudinally extending fold line as a typical blank advances at high speed along the paper line of the machine through the folding zone for the outer flaps.

Fig. 2 is a perspective view showing the method step of 30 making a helical face on a semi-circular channeled member by a longitudinally extending cut.

Fig. 2A is a perspective view of showing the method step of affixing a flat, straight bar guide onto the straight edge of the helically cut guide member.

Fig. 3 is a fragmentary end view in section on line 3—3 of Fig. 1 showing the initial stages of the folds in which each multi-purpose guide of this invention is holding down two tabs, or flaps, while serving as horizontal straight edges along the line of flap fold.

Fig. 4 is a view similar to Fig. 3, but insertion on line 4—4 of Fig. 1 showing a later stage in the fold.

Fig. 5 is a view similar to Fig. 3, but in section on line 5—5 of Fig. 1 and showing a still later stage in the fold, and

Fig. 6 is a view similar to Fig. 3, but in section on line 6—6 of Fig. 1 and showing the final stage of the fold.

As shown in the drawings, 20 is a portion of the frame of a typical box folding machine of the type in which flat box blanks are advanced horizontally along a paper line 21 either by the lugs of chains in timed machines, or by the friction of belts such as 22 and 23 in untimed machines. Untimed machines, such as that illustrated, do not require registration of the blanks and the blanks may therefore flow forwardly individually and successively at very high speed in the direction of the arrows, all in a well known manner forming no part of this invention. In the folding zone of the machine illustrated, outer flaps 24 and 25 are to be overfolded inwardly toward the centre of the blanks such as 26 on longitudinally extending lines of fold 27 and 28 and therefore the pair of conveyer belts 22 and 23 are trained around suitable pulleys such as 30, 31 and 32 supported in brackets such as 33, the bracket 33 being laterally slideable on a square shaft 34 by means of a thrust screw 35 in a well known manner.

The folding zone for the flaps 24 and 25 is defined by the folding belts 36 and 37 which extend longitudinally of the machine on opposite sides thereof and are driven by pulleys such as at 38 in the usual manner. Each belt such as 36 includes an upper stretch such as 39 which is outside the adjacent fold line 27 and is helically twisted to overfold an outer flap such as 24 as the flap and belt advance in the direction of travel of the blanks. The

flaps 24 and 25 are in the flat plane of the main body of a blank 26 when they arrive at the folder belts 36 and 39. However, the leading flaps and tabs of blank 26 have already been folded by preceding folding operations of the machine and a layer of adhesive has already been applied to such tabs or portions of the flaps as are designed to connect the blank into a collapsed box.

For clarity and convenience in this application, all diagonally articulated elements of the blank such as, at 42 and 43 are termed attachment, glue or adhesive tabs. In addition, all other articulated elements of the blank, to which such diagonally articulated tabs are intended to be adhered are also termed attachment, glue or adhesive tabs. The walls or panels of the blank to which such tabs are hingedly connected are termed flaps herein to distinguish the same from the attachment tabs. Thus it will be noted that in the particular blank 26 shown, the attachment tabs are designated 42, 43, 44 and 45 and the flaps to which they are articulated are designated 24, 46, 47 and 48. Tabs 44 and 45 and flaps 46 and 47 are all hingedly connected to blank 26 along a laterally extending fold line 50 which subsequently defines the bottom line of the collapsed box. The other laterally extending fold line 51 subsequently defines the top line of the collapsed box, the flaps articulated at line 51 being cover, closure, or sealing flaps. The glue tab 52 is used to complete the box when the blank has been folded into a collapsed tube by folding belts 36 and 37.

As outer flap 24 is overfolded on fold line 27 while advancing along paper line 21 at high speed it is necessary to retain outer tab 44 in overfolded position and to retain inner tab 42 and inner flap 46 in overfolded position to prevent fracturing or crushing the same. Similarly as outer flap 25 is overfolded on fold line 28 while advancing along paper line 21 at high speed it is necessary to retain outer tab 43 and outer flap 48 in overfolded position and to retain inner tab 45 in overfolded position. To assure the accurate folding of the flaps 24 and 25 on their fold lines it is also desirable to provide a straight edge along the inside of the fold line which prevents the flap from lifting the rest of the blank and failing to fold or misfolding.

The improved multifaced folding guide of this invention is designed to accomplish all of the above purposes with a single unitary guide for each such fold. The folding guides 53 and 54 are substantially identical except that they are reversed to each other. Each guide 53 is formed from a channel shaped, elongated, straight member 55 of self supporting material such as shown in Fig. 2. Preferably the walls of the member 55 are thin with rigidity being secured by the arcuate, arched shape thereof and the side edges at 56 and 57 are both initially straight and flat. The first step in the method of making the guide of this invention is the dividing of the member 55 into two sections by a longitudinally extending helical line of division which may extend from end to end thereof or from one end to a point further advanced therealong. Preferably this step is accomplished by cutting with a saw 58 and it should be noted that this operation is more simple, rapid and economical than milling a helical surface in a long bar or bending a rod into the correct helical shape. Each member 55 thus includes its original straight flat edge face such as 56 and the newly formed helical, but flat, edge face 59. A portion of original edge 57 is preferably retained as at 61 to give increased length to the resulting guide as shown in Fig. 1. Thus the non helical portion 61 serves to hold an outer flap down and flatwise while it advances from a preceding operation up to the fold belts 36 and 37.

The next step in the method of making the guide of this invention is the affixing of a straight, flat strip or bar 62 along the uncut, or non helical, straight edge face 56 of the member 55. The step is accomplished preferably by welding the edge 56 along the longitudinal centre line of the top face 63 of bar 62 to position the bar 62

in a radial plane relative to the semi-circular member 55 with one edge 64 of the bar extending along the imaginary longitudinal centre line 65 around which the member 55 outlines a semi-circle. Preferably the bar 62 is of thin, broad blue spring metal in order that it may yield resiliently if a blank jam occurs or if a blank must be forcibly removed from thereunder.

10 The folding guides 53 and 54, each formed by a member 55 fixed to a bar 62, are at least co-extensive with the longitudinal path of folding defined by the 180° twisted folder belts 36 and 37 and each is preferably additionally supported by a co-extensive angle iron such as 67 or 68 welded or otherwise affixed thereto. The guides 53 and 15 54, through the angle irons 67 and 68, are supported from above the paper line by brackets such as 70 and 71 in advance of the folding zone. Each bracket such as 20 70 includes a set screw 72 to permit slight longitudinal shifting of the guides and includes a portion 73 sleeved around square shaft 34 whereby it may be moved laterally by thrust screws such as 74.

25 The folding guides 53 and 54 are usually provided in a large size and a small size, each size accommodating a range of various sized blanks. As best shown in Figs. 3-6 the operation of the device is the same for flaps and tabs of various dimensions because the length of the folding zone is constant for all blanks and the helical path of the overfolded outer flaps corresponds to the helical face of the guide regardless of the length of the flap.

30 The operation of the device is best shown in Figs. 3-6 wherein it will be seen that Fig. 3 shows a blank 26 in the flat condition in which it enters the folding zone. The imaginary longitudinal centre line of the circle of which the members 55 are semi-circles lies along the path of the respective longitudinally extending fold lines 27 and 28 and the channel members are inverted as shown to straddle the fold line. This causes the non helically cut portion 61 of the edge 56 to hold down a longitudinally extending line of the upper face of the tab 44 without interfering with adhesive on the remainder of the upper face thereof. There is no friction between the member 55 and the portion of the upper face of tab 42 between the edges 61 or 59 and the fold line 27 and no adhesive wiping action occurs in this area of the tab. The flat underface 75 of the flat strip or bar 62 is positioned to hold down the inner tab 42 and the inner flap 46 as well as the wall 76 of blank 26 to which flap 46 is articulated. The hold down action of bar 62 extends laterally out to the outer, straight edge 64 of the bar which is as close as practicable to the path of the fold line 27 along paper line 21. The position and function of guide 54 is identical but reversed and it accomplishes the same three functions on its side of the path of the blanks.

35 In Fig. 4 the folding belts 36 and 37 have commenced to overfold flaps 24 and 25 inwardly toward the centre of the blank as the blank advances at high speed. The straight edge 64 is performing its function of assuring that the fold of the outer flaps takes place on the correct fold line 27 or 28 while underface 75 continues to hold the body of the blank and its overfolded elements down on the paper line. Helical face 59 continues to hold tab 44 flatwise against outer flap 24 while the helical face 59 of guide 54 holds both tab 43 and flap 48 down on flap 25.

40 Fig. 5 shows flaps 24 and 25 at the time they have been bent or folded along the correct fold lines 27 and 28 and shows underface 75 and helical face 59 continuing to hold the over-folded tabs and flaps flatwise against their respective flaps 24 and 25. It is at this point in the fold that if either tab 44 or 42 were not held down, their slight unfolding would cause them to be crushed or to fold on a new and undesirable line of fold.

45 In Fig. 6 the folding of outer flaps 24 and 25 has been completed, with the attachment tabs adhesively connected together and the blank, formed into collapsed tubular condition. The collapsed completed boxes then

pass out of the folding zone in a manner well known in the trade.

I claim:

1. A unitary, multiple, folding guide for controlling the tabs and flaps of a plurality of box blanks advancing individually and successively along a path through the flap folding zone of a folding machine, said guide comprising an elongated body of self supporting material coextensive in length with said folding zone, said body having a flat, straight, strip extending the full length of one side thereof with a smooth underface and at least one straight edge and said body having an arched strip with a straight edge face affixed centrally of the upper face of said flat strip and a helical edge face commencing on the opposite side of the longitudinal axis of said body from the straight edge face thereof, at one end, but crossing over said longitudinal axis to merge with said straight edge face at the other end of said body and means for supporting said guide above the path of said blanks with said arched strip straddling the longitudinal path of the fold line of the flap being overfolded in said zone, the straight edge of said flat strip just inside said path and the underface of said flat strip just above the path of the main body of said blanks.

2. A combination as specified in claim 1 wherein said flat strip is of spring metal and adapted to yield for the removal of a blank jammed thereunder.

3. A combination as specified in claim 1 wherein said arched strip is formed of thin walled material whereby the helical edge face thereof is narrow and engages only a narrow strip of an adhesively coated tab being guided thereby.

4. A combination as specified in claim 1 wherein said arched strip is of semi-circular configuration at one end thereof and of parti-circular configuration in the remainder thereof.

5. A combination as specified in claim 1 wherein said guide supporting means includes threaded mechanism for moving said guide longitudinally and laterally relative to the path of said blanks through the folding zone of said machine.
